Primary Examiner — Karen S Acker*Assistant Examiner* — Elizabeth Sun Ko(74) *Attorney, Agent, or Firm* — Sand, Sebolt & Wernow Co., LPA(57) **CLAIM**

The ornamental design for a rack for supporting router bits, as shown and described.

DESCRIPTION

FIG. 1 is a top front right side perspective view of the rack for supporting router bits in accordance with my design; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; and, FIG. 7 is a bottom plan view thereof.

The broken lines illustrate portions of the rack for supporting router bits which form no part of the claimed design. The claimed design is shown with a symbolic break in its length. The appearance of any portion of the article between the break lines forms no part of the claimed design.
